UNITED STATES PATENT OFFICE.

RAYMOND PIERRE LOUIS SENG, OF PARIS, FRANCE.

DOUBLE-ACTING LATCH.

Application filed April 28, 1926, Serial No. 105,324, and in France May 13, 1925.

This invention relates to double acting latches designed to lock and release automatically a fixed and a movable member.

One of the objects of the invention is to provide a locking and releasing latch capable of functioning automatically with the opening or closing movement of the movable member.

Other objects will appear in the course of the detailed description which will now be given with reference to the accompanying drawings in which:

Figure 1, shows a front view of the latch in the releasing position;

Figure 2, is a side view of the latch in the position shown in Figure 1.

Figure 3 is a sectional view of the latch as shown in Figures 1 and 2.

Figure 4, shows in section the latch in the latching position; and

Figure 5, is a section of the shaft which supports the spring latching mechanism.

Considering Figures 1 to 5 of the drawings, there is shown a movable wall member 1 provided with a handle P and a fixed member 2 provided with a U-shaped member 17. The latching mechanism comprises a base 3 screwed, bolted or otherwise attached to member 1, a pair of lateral members 6 mounted, preferably, integrally on base 3, a bar 20 extending between members 6 and fastened to the latter by means of suitable nuts or by being made in the form of a bolt having a head 7 and a fastening nut 7^a. A set of sleeves 21, 23, 23 and washers 24, 24 are mounted on bar 20, which carries a latching member 9 having a longitudinal slot 19 therein and a transverse bar 22 at one end from which springs 10 extend to bar 20.

The end of latching member 9 is designed to engage the U-shaped member 17 and is provided with a pair of projections 9^a, 9^b limiting a recess 26. A deflecting member 18 is provided for insuring proper movement of U-shaped member 17 in relation to the latching mechanism and a boss 25, arranged on base 3 so as to come opposite recess 26 when the latter is in its lowermost position, deflects member 17 into recess 26.

The manner in which the above described elements cooperate to lock and to release the fixed and movable members is as follows:— Starting from the position shown in Figures 1 to 3, that is to say, with latching member 9 inclined downwardly toward fixed member

2 and assuming that pressure is exerted downwardly on handle P, U-shaped member 17 will move into the space between base 3 and deflecting member 18 and, under the guidance of the latter, will approach recess 26. As soon as member 17 arrives opposite boss 25, it will be deflected into recess 26. Continued pressure on handle P will now cause the latching member 9 to move toward a horizontal position against the action of springs 10. As soon as member 9 passes the "dead point" i. e. the exactly horizontal position, spring 10 will tend to force the latching member into the position shown in Figure 4 and member 1 will be brought firmly into contact with member 2. The movements necessary to release members 1 and 2 from one another take place in the reverse order to those described for the latching operation and need not therefore be described.

From the foregoing description, it will be clear that there is here provided a mechanism for automatically latching and releasing a pair of members by simply moving one of the members toward or away from the other.

The invention is thought to be particularly applicable to the hoods of automobile engines or to similar construction where it is desired to latch two members together by simply bringing one down forcefully on the other. The invention is not however to be considered as being limited to such uses but may be employed as well on roll-top desks, on windows, on shutters and for any desired latching purpose.

Having now particularly described and ascertained the nature of my said invention and in what manner the same is to be performed, I declare that what I claim is:

1. In a double acting latch, a fixed latch member, a base having wings supporting a transverse pivot, a slotted latch member mounted upon said pivot and provided at its free end with a seat, a spring extending from the opposite end of said latch to said pivot to project the latch into contact with the base, a hasp member disposed to travel parallel with said base and to enter said seat for retention therein when the latch is shifted to locked position, a guide wall upon said wings, and a projection upon the base opposite said seat when the latch is in open position and disposed to direct said hasp member into said seat.
2. In a double acting latch, a fixed latch

member, a base having wings projected laterally therefrom, a transverse pivot connecting said wings, a movable latch having a slot mounted upon said pivot, means connecting said latch with the base for projecting the latch into contact therewith, a seat at the end of the latch next the base adapted to receive and retain the fixed latch member against

lateral displacement, an inclined guide at the lower portion of said wings, and a projection 10 upon the inner face of the base disposed in alignment with said seat when the latch is in open position.

In testimony whereof I affix my signature.

RAYMOND PIERRE LOUIS SENG.
